ATTACHMENT FOR GARMENT PRESSING
MACHINES

Harry G. Sutton, Syracuse, N. Y., assignor to
United States Hoffman Machinery Corpora-
tion, New York, N. Y., a corporation of Dela-
ware

Application August 9, 1935, Serial No. 35,549

4 Claims. (Cl. 68—9)

This invention relates to garment presses, and pertains more particularly to an improved means for effecting a non-spotting distribution of steam from one or another of the pressing elements of the press, which steam is commonly utilized to dampen the goods or articles to be pressed, or to raise the nap or pile of various textiles such as serges, velvets and the like.

I am aware that heretofore various so-called "press plates" and "screens" have been devised to effectuate the object above specified, but their use as a rule produces markings on certain goods, which markings are commonly known in the trade as "nickel spots".

The main object of the present case is to produce a structure which, while it may be readily positioned upon a pressing element of a pressing machine, will produce that even distribution of steam which is essential to the proper treatment of the goods or garments and which, moreover, precludes the production of nickel spots.

The plate of my invention is illustrated in the annexed drawing, wherein:—

Figure 1 is a face view thereof as seen from the innermost side, or that which lies next adjacent the press element, say the steam heated head;

Fig. 2, a transverse sectional view of such a head with the press plate positioned thereon; and Fig. 3, a perspective view of a portion of the usual undermost perforate plate or element of the head with a section or portion of the press plate in position with relation thereto.

In the drawing 10 denotes the press head having a steam heating chamber 11 formed therein, steam passing thereto and through the same through suitable piping, not shown.

Permanently secured to a downwardly extending flange 12 of the head 10 is a perforate plate 13, said plate, flange and under face of the head forming a chamber 14, which is in communication with the chamber 11 through a valve 15, which is of the standard type and normally closes off the passage of steam from the heating chamber 11 to the spray chamber 14. When the valve is opened, however, steam may pass through the valve from chamber 11 to chamber 14 and through perforations 16 formed in the plate 13.

The construction thus far described is of the usual type.

The press plate of my invention embodies or comprises a plate 17 of comparatively light gauge and having a series or plurality of perforations 17^a extending therethrough, said perforations be-

ing small as compared to the openings 16 in the element 13.

The plate 17, as will be most clearly seen upon reference to Figs. 2 and 3, has its outer edge upturned as at 18 and secured to said plate and upturned or flanged portion is a grid or screen, preferably formed of non-corrosive, fine mesh woven wire. Such grid or screen is denoted by 19. It is carried entirely beneath the plate 17 upwardly past the flange 18 and about two retaining wires or bands 21 and 22 which are bent to conform to the contour of the head or upper portion of the flange 12, each band extending approximately half-way around the same.

The end of each section 21 and 22 is formed into an eye and bolts 23 and 24 are passed through the adjacent eyes, thumb nuts 25 being provided to permit ready adjustment of the plate to the head of the machine.

The grid or screen 19 at its inner margin is carried downwardly and overlaps the upstanding flange 18 and small rivets 26 are passed therethrough, so that the screen or grid is rigidly affixed and secured to the flange 18 of the plate 17. In this manner, the press plate or screen may be readily handled with a view of positioning it on the head, or removing it therefrom.

While the bands or wires 21 and 22, together with the bolts 23 and 24, provide a ready means of drawing the plate to position upon the head, or in that position shown in Fig. 2 wherein the bands 21 and 22 overlie the upper edge of the flange 12, one or more coiled springs as 27 may be utilized, the same being attached at opposite ends through links 28 and bails 29, the latter being pivoted or secured upon the respective bands 21 and 22.

Assuming that the press plate is secured in position upon the head of the press and steam is permitted to pass through the valve from the chamber 11 to the chamber 14, it will, owing to its pressure, pass outwardly through the openings 16 and contact the plate 17, passing thereover or between the lower face of the plate 13 and the upper face of the plate 17 until it comes to the small openings 17^a through which it passes to the screen or grid 19.

The arrangement of the relatively small openings in the plate 17, together with the underlying screen, secures a substantially even distribution of the steam over the entire face of the pressing head, and, consequently, an even distribution to all parts of the garment which may be in contact with the screen at such time. By reason of this even distribution, the so-called

"nickel spots" are eliminated; or, stated in another way, are not produced.

Not only is there better diffusion of steam brought about by the plate 17 with its small orifices when employed with the grid or screen 19, but as above indicated, no spotting of the garment takes place and if the goods undergoing treatment are shiny, the shine is eliminated therefrom.

10. Insofar as the fastening or securing means for the screen is concerned, other means may be employed, the essential feature being the screen construction as above described.

15. Preferably, the plate 17 and the wire screen will be produced from non-corrosive metal, and by reason of the fact that the plate 17 is flanged and the wire or screen is permanently secured thereto as by the rivets, the structure presents that degree of stability which enables it to be readily handled and positioned upon a pressing element of the garment pressing machine. So, too, there is no opportunity for the members 21 and 22 to become displaced, as they are encased within the folded over portion of the screen, which folding 25 over of the rounded surface of the rods or cables presents a smooth finished edge to the structure.

It is to be understood that the plate 17 could be made to conform to any desired configuration of the pressing member with which it is to be employed.

What is claimed is:

1. In a device of the class described, the combination of a plate having perforations therein and having its marginal portions flanged; a wire screen extending across the under face of said plate and upward along the flanged portion thereof; means for securing said wire screen to said flanged portion; and means for securing the structure thus produced to the head of a pressing element of a garment pressing machine.

2. In a structure of the class described, the

combination of a plate having a plurality of small perforations extending therethrough, said plate at its edges being flanged in an upward direction; a wire screen underlying the plate, said screen extending upwardly beyond the upper edge of the flange of the plate and being turned back upon itself and embracing the flange; and means for securing the flange and the embracing portions of the screen together.

3. In a device of the character described, the combination of a plate having a series of small perforations formed in and extending therethrough, the outer edge of the plate being flanged in an upward direction; a wire screen underlying said plate, said screen likewise extending upwardly against the outer face of the flanged portion of the plate, and said screen being folded back upon itself and over the flanged portion of the plate, with the lower marginal portion thereof lying against the inner face of the flange of the plate; and a series of rivets extending through the upstanding flange aforesaid and through those portions of the screen which lie against the opposite faces thereof.

4. In a device of the character described, the combination of a plate having an upstanding flanged edge, said plate likewise having a plurality of small perforations extending therethrough from its upper to its lower face; a screen extending beneath and contacting the lower face of the plate and extending upwardly past and in contact with the flanged portion of the plate, the edge of the screen being folded back upon itself so that the marginal portion thereof lies against the inner face of the flange of the plate; a plurality of rivets passing through the flange and the adjacent portions of the screen; and a band encased within the infolded portion of the screen above the upper edge of the flange of the plate.
